UNITED STATES PATENT OFFICE.

EUGENE VERMILYEA, OF WATERFORD, ASSIGNOR TO CAMPBELL & CLUTE,
OF COHOES, NEW YORK.

ADJUSTABLE SUPPORT FOR THE CLOTH-WHEELS AND BURR-WHEELS OF ROTARY KNITTING-MACHINES.

SPECIFICATION forming part of Letters Patent No. 508,452, dated November 14, 1893.

Application filed October 3, 1892. Serial No. 447,608. (No model.)

To all whom it may concern:

Be it known that I, EUGENE VERMILYEA, of the village of Waterford, county of Saratoga, State of New York, have invented new and 5 useful Improvements in Adjustable Supports for the Cloth-Wheels and Burr-Wheels of Rotary Knitting-Machines, of which the following is a specification.

My invention relates to mechanism whereby the sinker-burrs and cloth-wheels of rotary knitting machines when mounted upon a standard that is upwardly projected from the machine table or bed, are each made separately adjustable with relation to the needles 15 and cloth; and the object and purpose of my invention are to so arrange and construct the sinker-burr standard supports that the burrs as held in an elastic engagement with the needles may be moved toward or from the latter, 20 or may be deflected either to the right or left by a rotation of its holder, or so that the burr may be raised or depressed on an angle where adjacent to the needles; and when so adjusted may be secured in such desired position, and 25 with the cloth-wheel support so arranged that the wheel may be raised, or depressed, or caused to engage with the cloth inside of the needles at such angle as is desirable; or to be moved laterally so as to bring the landing 30 wheel and presser-wheel close up to the sinker-burr.

Accompanying this specification to form a part of it there are three plates of drawings containing seven figures illustrating my invention with the same designation of parts 35 by letter reference used in all of them.

Of the illustrations Figure 1 is a side elevation of the apparatus containing my invention shown as applied to a knitting machine, 40 which latter is shown in part. Fig. 2 is a central vertical section of the apparatus taken from end to end with the burr shown as turned up abnormally and away from its engagement with the needles. Fig. 3 is a front elevation 45 of the mechanism. Fig. 4 is a perspective of the standard to which the mechanism attaches. Fig. 5 is a perspective of a bracket that attaches to the front of the standard when 50 in position. Fig. 6 is a perspective of the shaft on which the arm that supports the burr-holder is hinged or pivoted and on which

it is operated to raise or depress the burr. Fig. 7 is a perspective of the clamp and arm in which the burr-holder cylinder is held and operated to be raised or lowered.

55

The several parts of the apparatus thus illustrated are designated by letter reference and the function of the parts is described as follows:

The letter S designates a standard that is 60 upwardly projected from the machine table T.

The letter C designates the knitting machine cylinder; the letter N one of the needles in position, and F the fabric.

The letter B designates a bracket made 65 with a vertical slot M, by which said bracket when vertically adjusted to proper position on the standard is secured thereon by a threaded bolt d, made with a nut-form head I.

The letters E designate ears formed on the 70 sides of the bracket oppositely, and vertically; and the letters b³, bearings oppositely formed in the ears E to be horizontally in line for the journals J of the shaft S², when placed thereon, one of said journals being 75 threaded to enter the tapped end of said shaft for its insertion in its bearings.

The letter N² designates a set-screw, tapped and threaded into one of the front ends of 80 one of the ears E, so that when said set-screw is screwed in, it will engage with one of the journals of the shaft S², and prevent it from turning. This shaft S² is centrally, and at 85 its top and bottom, made with recesses R, which have flat parallel surfaces, and a central passage p², made through the shaft at right angles to the inner surfaces of the recesses R.

The letter A designates a vertically arranged arm that at its lower end is made with 90 a shoulder h, and where reduced in diameter by the formation of the shoulder, this arm passes through the passage p², made in the shaft S², with the shoulder h, of the arm A, resting upon the flat surface of the recess R, 95 made in the top of said shaft S², and where extending through said passage p², is threaded to receive a nut n², and keeper k.

The letter C² designates a clamp formed on the upper end of the arm A, said clamp being made with a circular passage p³, and 100 pinch-screw y².

The letters H designate the burr-holder cylinder, that is placed within the clamp passage p^3 , of the arm A, and held there by the pinch screw y^2 , and this cylinder has an interiorly constructed and encircling recess h^3 , in which is placed a spiral spring h^2 , with one end of the latter bearing against the end e^2 of the recess h^3 .

The letter h^4 designates the burr-holder proper, which is arranged within the cylinder H, and is made with a shoulder h^5 , against which latter the end e^2 , of the spring h^2 , bears, so that when said burr-holder proper is moved outwardly it is so moved against the force of said spring. The outer end of this burr-holder proper is threaded at t^2 , and has threaded thereon the jam-nut h^6 , and the adjusting nut h^7 , by which the burr-holder proper may be regulated as to its adjustment radially to the needle cylinder and by which also the force of the spring encircling it is controlled. The inner end of the burr-holder proper has formed thereon an offset extension h^8 , to receive the spindle h^9 , and the sinker-burr B².

The letter O designates a slot made in the standard S, through which the holder cylinder H, and the burr-holder proper may be moved when raised or depressed at the outer end. As thus made and arranged through the sliding connection it makes with the arm A, and the journaled connection the latter makes with the bracket B, the burr-holder may be raised or lowered to bring the blades of the sinker-burr in longer or shorter engagement with the needles, and by means of the set-screw N², the position of the burr relative to the needles may be secured as adjusted; and by means of the connection the burr-holder makes with the clamp C², the holder and its cylinder may be turned in said clamp to vary the position of the burr-blades to the needles and be secured as adjusted by the pinch-screw y².

The letter W, designates a cloth-wheel having a disk-form and made with a frontwardly projecting sleeve w². The letter w³, designates a spindle on which said wheel and its sleeve turn, said wheel being secured on said spindle by a nut w⁴, on the inner end of said spindle, and a collar w⁵, having a set-screw w⁶, so that the wheel is free to turn on its spindle from the traction engagement it makes with the moving cloth.

The letter K designates a clamp formed on the outer end of the spindle w³.

The letter A² designates a crank-form arm, the upper and vertical end of which as indicated at a³, is inserted in the clamp K, and on which the latter and its spindle w³, may be raised or lowered to elevate or depress the cloth-wheel W, and held as so adjusted by the pinch-screw y, of said clamp K.

The letter a⁴ designates the horizontal extension of the crank-form arm A², that is made to journal in a horizontal bearing b⁶, made in the bracket-form projection upcast from the standard S. This bearing is con-

structed with a set-screw T⁶, that is tapped and threaded into said bearing so that it will engage with the arm a⁴, where journaling 7⁰ within the latter, and in which, when the set-screw therein is free from the journal part, said arm may be moved horizontally therein, and secured by the set-screw when adjusted, and by which construction the cloth-wheel 75 may be moved laterally and positioned with reference to the needles and the landing-wheel (not shown) as may be desired. As thus made and arranged the sinker-burr may be positioned so as to have the needles enter 80 deep between the burr-blades so as to leave little play and thus produce short stitches, or to enter the upper part of the space between the blades so as to make a long stitch according to the pitch at which the burr-blades are 85 adjusted by my improvement; and when live yarn or silk is used and it is desirable to bring the presser-wheel and landing-wheel as close to the sinker-burr as possible, the cloth wheel, by my improved construction may be moved 90 laterally to thus admit of such placing of the presser-wheel and landing wheel with reference to the sinker-burr.

Having thus described my invention, what I claim, and desire to secure by Letters Patent, is—

1. The combination with the cylinder of a rotary knitting machine, of a standard upwardly projected from the machine table, a crank-form arm having a horizontal part journaled into an offset from said standard, in which the said horizontal part of said crank-form arm can turn or be moved horizontally; a set-screw arranged in said offset adapted to engage with said crank-form arm; a clamp 105 provided with a spindle shaft and pinch-screw, said clamp making a sliding and a stationary engagement with the vertical part of said crank-form arm; and a cloth-wheel arranged to turn on said spindle, substantially 110 in the manner as and for the purposes set forth.

2. The combination with the cylinder of a rotary knitting machine, of a standard made with a slotted passage; a burr-holder cylinder arranged in said passage; a burr-holder having a sinker-burr mounted on its inner end, and arranged within said cylinder; an arm which at its lower end is provided with a shaft and bearings in which to oscillate, and at its upper end is constructed with a clamp 120 and pinch screw in which clamp said burr-holder cylinder and burr-holder may turn or slide for adjustment, and on which journaled connection of the arm the latter and burr-holder and burr-holder cylinder can be moved 125 to raise or depress the inner end of the burr-holder substantially in the manner as and for the purposes set forth.

3. The combination with the cylinder of a knitting machine, of a standard upwardly projected from the machine table, a burr-holder mounted in a cylinder, and having on its inner end a burr-spindle and a sinker-burr, said burr-holder cylinder having an adjustable

connection with said standard by which it and the burr-holder may be turned or moved back and forth, and a journaled connection by which its inner end and the burr thereon 5 may be raised or depressed substantially as described; and a crank-form arm having its horizontal part arranged in a bearing on said standard in which to be moved horizontally; and the vertical part of said crank-arm provided with a spindle and clamp, with the latter adjustable on said vertical part; and a cloth-wheel arranged on said clamp spindle, substantially in the manner as and for the purposes set forth.

15 4. The combination with the standard S, having the passage-way O, the bracket B, made with hinging ears E, E; the shaft S², made to journal in the latter; the up-cast arm A, at its lower end connected to said shaft, 20 and having the burr-holder clamp c², and pivot-screw y², at its upper end; the cylindrical

holder-part H, arranged within said clamp; the burr-holder proper h⁴ having the spindle h⁵, and sinker-burr B², on its inner end, made with the encircling recess h⁸, and arranged 25 within the cylindrical holder; the spiral spring h², arranged to encircle said holder proper within said recess; the adjustable nut h⁷, threaded on to the outer end of the holder proper where extending beyond the cylinder, 30 and the jam-nut h⁶, on the outer end of the holder proper outside of the adjusting nut substantially in the manner as and for the purposes set forth.

Signed at Troy, New York, this 21st day of 35 July, 1892, and in the presence of the two witnesses whose names are hereto written.

EUGENE VERMILYEA.
